UNITED STATES PATENT OFFICE.

JOHN EDWIN PROSSER, OF TULSA, OKLAHOMA.

DRILLING-BIT.

1,104,543.

Specification of Letters Patent. Patented July 21, 1914.

Application filed October 7, 1913. Serial No. 793,657.

To all whom it may concern:

Be it known that I, JOHN EDWIN PROSSER, a citizen of the United States, and a resident of Tulsa, in the county of Tulsa and State 5 of Oklahoma, have invented a new and useful Improvement in Drilling-Bits, of which the following is a specification.

My invention is an improvement in drilling bits, and has for its object to provide a 10 bit of the character specified, especially adapted for use in drilling deep wells, as for instance, oil or gas wells, wherein the bit is provided with water courses extending from the connected to the cutting end in 15 spiral form.

In the drawings:—Figure 1 is a view of the improved bit. Fig. 2 is a view at right angles to Fig. 1. Fig. 3 is an end view looking at the cutting end, and Fig. 4 is a section on the line 4—4 of Fig. 2.

In the present embodiment of the invention the bit consists of a body 1 of cylindrical form, provided with spiral grooves 2, the said grooves extending from one end 25 of the body to the other and being directly opposite each other throughout their course. At the cutting end of the bit, the cylindrical body is reduced and flattened to form opposite parallel faces 3, and shoulders 4 are 30 formed between each of the flattened surfaces 3 and the body of the bit. The grooves 2 are of greater depth than the width of the shoulders 4, as shown more particularly in Fig. 3, and the spiral course of the grooves 35 ends at the said shoulders 4. Each of the flattened faces 3 is grooved longitudinally as shown at 2^a, to form a continuation of the adjacent groove 2. Below the faces 3, the bit is beveled to form a cutting edge 5, 40 and the said edge is of slightly greater length than the diameter of the body 1 of the bit as shown in Figs. 2 and 3. At the end remote from the cutting edge, the bit is reduced as shown at 6, and an annular 45 shoulder 7 is formed between the body and the reduced portion. At the ends of the grooves 2, the reduced portion is flattened on opposite sides to form plane faces 8, the said faces 8 being at right angles to the 50 faces 3 at the opposite end, and each of the

grooves 2 opens at one of the surfaces or faces 8. Beyond the reduced portion 6, the bit is again slightly reduced as shown at 9, and a threaded stem 10 is provided beyond the surface 9.

The improved bit is designed to be connected to the lower end of the drilling stem, and is used in the ordinary manner. As the bit cuts, it is partially rotated, and water is fed to the cutting point through the grooves 55 2—2^a, if water is not already present.

As the cutting edge separates or breaks away portions of the rock, the said portions are thoroughly mixed with the water, the mixed stone and water, passing up through 60 the grooves 2. The action of the water or the mixture above mentioned, assists in rotating the bit.

All of the matter cut away by the cutting edge may pass freely upward through the 65 grooves, so that there is no danger of jamming or choking the drill. The bit may thus cut to a much better advantage, since the cutting action is not hindered by the matter already separated. When the bit 70 becomes dull, the cutting edge may be sharpened in the usual manner.

I claim:

1. A drill comprising a body of approximately cylindrical form having one end reduced on opposite faces to form oppositely arranged approximately parallel surfaces, said body having a cutting edge beyond the said surfaces, and the body having spiral grooves, extending to the said surfaces, and the said surfaces being grooved longitudinally to form continuations of the spiral grooves, said body being annularly reduced at the opposite end and the grooves opening at the reduced portion, said body having a 80 threaded shank at the end remote from the cutting edge.

2. A drill comprising a body of approximately cylindrical form having one end reduced on opposite faces to form oppositely arranged transversely parallel surfaces, and having a cutting edge beyond the said surfaces, the opposite end of the body being annularly reduced, and the body having spiral grooves extending from the annularly 85 90 95 100

2 reduced portion to the said surfaces, the said surfaces being grooved longitudinally to form continuations of the spiral grooves.

3. A drill comprising a body of approximately cylindrical form having one end reduced on opposite faces to form oppositely arranged transversely parallel surfaces, and having a cutting edge beyond the said sur-

faces, the opposite end of the body being annularly reduced, and the body having 10 spiral grooves extending from the annularly reduced portion to the said surfaces.

JOHN EDWIN PROSSER.
